UNITED STATES PATENT OFFICE.

EDWARD D. PUTT, OF AKRON, OHIO, ASSIGNOR TO THE FIRESTONE TIRE AND RUBBER COMPANY, OF AKRON, OHIO, A CORPORATION OF OHIO.

TIRE-FINISHING MACHINE.

Application filed July 13, 1923. Serial No. 651,289.

This invention relates to the art of tire manufacture and particularly to that portion of what is known as the finishing operations, in which the side-walls and chafer strips are applied. Heretofore, as far as has come to my knowledge, these operations have been performed by hand and it is the purpose of the present invention to substitute machine operations for the hand operations and to do the work faster and more accurately than by hand.

In the drawings and description there is disclosed one form or embodiment of my invention, it being understood that the showing is for the purpose of illustrating the invention and not for restricting it to exact conformance therewith.

In the drawings:

Figure 1 is a side elevation of a unit which comprises two of the finishing machines with a common motor drive;

Figure 2 is an enlarged side elevation of the upper part of the machine looking at the feeding-in side;

Figure 3 is a similar view looking at the opposite side of the machine;

Figure 4 is a plan view of the machine;

Figure 5 is a side elevation, partly in section, showing the material applying rollers in inoperative position;

Figure 6 is an enlarged front elevation of the rollers for turning the chafer strip around the toe of the bead;

Figure 7 is an end view of the rollers shown in Figure 6;

Figure 8 is a side elevation of the chafer stitching and rolling mechanism;

Figure 9 is a plan view of the stitching and rolling mechanism with a portion of the stitcher removed to illustrate the stitching wheel.

In the present embodiment of my invention selected for illustration, I have shown two of my finishing machines driven from one motor and so constructed that they comprise a unit. Both machines are alike and a description of one will apply to the other.

Referring now to the drawings in which like characters of reference designate simi-

lar parts, 2 designates a base on which is mounted a hollow column 4. Upon the upper end of the column 4 is shown a head 6 suitably shaped and constructed to receive and support the various working parts of the machine comprising my invention, the head being provided with a removable cover plate 8 to allow the assemblage of the driving mechanism to be described hereinafter. Extending through a bearing 10 integral with the head 6 is a horizontal shaft 12 having upon its outer end a roll 14 which supports and rotates the tire casing 1. The shaft 12 is provided upon its inner end with a bevel gear 16 which meshes with a gear 18 upon the upper end of vertical shaft 20 arranged within the machine column and provided upon its lower end with a gear 22 in mesh with a gear 24 upon a horizontal drive shaft 26 conveniently mounted upon the base of the machine. The shaft 26 is connected to any suitable source of power, the preferred embodiment illustrated being shown as an electric motor 28.

Pivoted at 30 upon a bracket 32 arising above the head of the machine is an arm 34 which terminates in a downwardly extending portion 36 to provide a suitable bearing 38 for a horizontal shaft 40 arranged above the shaft 12 and which is substantially parallel thereto when in operative position. Loosely mounted upon the shaft 40 is a side-wall pressure roll 42 comprising a cylindrical body portion 44 preferably covered with a yielding work-engaging surface of rubber, or similar material, and having an integral guide flange 46 constructed to engage the heel of the bead.

Mounted upon the shaft 40 adjacent the roll 42 is a bead engaging roller 48 substantially frusto-conical in outline to conform to the surface 50 of the bead, and adapted to lay the chafer strip B smoothly thereon. The roll 48 is yieldingly urged toward the roll 42 by a spring 52 surrounding the shaft 40 and confined between a collar 54 and the inner end of the roll. This construction allows the roll 48 to yield relative to the roll 42, a circumstance rendered sometimes neces-

sary by a variance in the size of the bead and the thickness of the chafer strip.

In order to facilitate the presentation to and removal of the tire casing from the machine, provision is made for moving the pressure rollers bodily toward and from the supporting roller. To this end the arm 34 is provided with studs 56 on which are pivoted parallel links 58 connected together by cross bars 60 having reduced ends which extend through suitable holes in the links and are secured in place by cotter pins 62. To the lower end of the links 58 is attached a hook 64 for connection with a treadle lever 66 pivoted at 68 to a bracket 70 upon the base of the machine. A spring 72 having one end connected to the links 58 and the other secured to the machine column serves to maintain the pressure rollers normally in their elevated position, it being evident that downward movement of the foot treadle will cause the rollers to approach the supporting roll 14 and engage the side-wall and bead of the tire.

In the operation of the machine, the supporting roll 14 is constantly driven and thus will cause the casing 1 placed in engagement therewith to be rotated. It is necessary, however, at certain stages in the operation to have the casing remain stationary, such a condition being desirable, for example, when the side-wall and chafer strip are being started on the casing and during the splicing operation when the adjacent ends are being connected. To this end, an angular lift arm 74 is rigidly connected to one of the cross bars 60 and is adapted to engage the inner side of the casing and elevate the latter above the supporting roll 14 whenever the pressure rollers 42 and 48 are in inoperative position. Simultaneously with the downward movement of the pressure rollers toward the casing, the lift arm 74 retreats and allows the casing to engage the supporting roll 14 and be rotated thereby.

It will be understood by those familiar with the manufacture of pneumatic tires, that the side-wall strip is extremely tacky and that precaution must be used to prevent the strip from contacting with the casing prior to being placed in the position it is to finally assume thereon. To prevent the undesirable contact above mentioned, as well as to aid the operative in properly placing the strips, a separating bar 76 is shown arranged above the tire casing, the strips being passed over the bar into the machine and thus kept separated from the casing until a point immediately preceding the effective surface of the pressure rollers 42 and 48 is reached. The guide bar 76 is mounted upon the upper end of a vertical stud 78 which is carried by a link 80 pivoted at 82 to the frame of the machine. Thus it will

be evident that the separating or guide bar 76 may be readily swung about the pivot 82 to bring it into or out of operative position. Upon the lower end of stud 78 and separated from the guide bar by a washer 84 is a guide roller 86 adapted to engage the toe of the bead and locate the casing in proper position.

The effect of the pressure rolls 42 and 48 is to press the side-wall A and chafer strip B firmly against the side of the casing and over the heel and face of the bead. In addition to the above mechanism, the finishing mechanism includes means for smoothing the chafer around and stitching it under the toe of the bead, an operation exceedingly difficult to perform by a machine due to the tendency on the part of the chafer strip to wrinkle upon its application to this part of the bead. In the present embodiment of the invention, a series of rollers 90 are positioned substantially tangentially to the bead, the axis of each successive roller being arranged more nearly to vertical position than the preceding one so that the chafer strip will be gradually smoothed down around the toe of the bead and after passing the last roller 90 will hang substantially perpendicular to the inner surface of the casing. The turning rollers 90 are mounted in a casing 92 secured by a bracket 94 to the frame of the machine.

The stitching mechanism illustrated for wiping the chafer strip under the toe of the bead comprises a member 96 in the form of the frustum of an inverted cone, upon the small end of which is formed a toothed stitching wheel 98 having a diameter substantially equal to the base of the cone, the periphery of the stitching member being shaped to conform to the cross-sectional shape of the toe of the bead. The stitching member 96 is driven by the toe of the bead which is forced into frictional engagement with the stitching member in a manner to be described hereinafter. The stitching wheel 98 wipes or kicks the loose flange C of the chafer strip under the toe of the bead, it being at once evident that since the periphery of the wheel is greater than that portion of the stitching element engaged by the toe of the bead, the speed of the former will be greater than the travel of the bead and as a result the chafer strip will be wiped under so rapidly that all chance of a piling up or wrinkling thereof by the wheel will be eliminated.

The stitching mechanism 96 is freely rotatable on a vertical stud 97 supported in a bracket 100 which in turn is supported by a second bracket 102 fixed to the standard of the machine.

After being turned back under the bead, it is desirable to roll the chafer strip down firmly. To this end a roller 104 is mounted

to rotate upon a horizontal stud 106 carried by bracket 102, the roller 104 being adapted to extend within the tire casing and press the chafer strip against the inner side of the bead.

It is necessary in the successful operation of the above described mechanisms to keep the tire bead into proper position with relation thereto, and to constantly crowd the tire casing toward the left in Figure 3 so that the bead will engage the rollers 90 and the stitching mechanism to effect the proper operation thereof. As a means for accomplishing this result, novel guiding means are employed which consist of a cylindrical roller 110 and a frusto-conical roller 112 arranged on opposite sides of the driving and supporting roll 14, the axes of the first named rollers being tilted with respect to the radial line of the tire, thus causing the latter to be urged constantly toward the operating instrumentalities in a manner clearly understood.

In order to further facilitate the guiding of the tire casing, a plurality of rollers 114 and 116 having the axes thereof at right angles to one another are provided at one side of the machine, the roller 114 being arranged to engage the side and the roller 116 the tread of the casing. An adjustment block 118 is arranged between the guide rollers and a supporting rod 120 whereby the rollers may be adjusted to meet the requirements of various tires.

Conveniently mounted in brackets 122 upon the rear of the machine column is a vertically arranged guide roller 124, the purpose of which is to facilitate the rotation of the casing and prevent injury thereto.

While the operation of the different mechanisms and the cycle of the machine as a whole have been set forth in the foregoing description, they may be summarized briefly as follows:

The usual side-wall A and chafer strip B are assembled in any desirable manner to form a unit prior to the application thereof to the tire casing. A tire casing 1, to which the side-wall and chafer strip are to be applied, is passed over the head of the machine and arranged with one side thereof above the driving roll 14 in the manner illustrated in Figure 5. The separating and guide bar 76 is swung into position and the end of the previously assembled side-wall and chafer strip is properly secured to the casing by the operative. Upon depression of the treadle 66, the lift bar 74 will retreat and permit the driving roll 14 to rotate the casing, carrying therewith the side-wall and chafer strip which are guided into proper position by the operator as they are pulled through his hands. Simultaneously with the rotation of the casing, the pressure

rollers 42 and 48 will be moved downwardly 65 and roll the side-wall and the chafer strip to the side of the casing and outer face of the bead respectively. The tilted rollers 90 will now gradually turn the overlapping flange C of the chafer strip into position to 70 be swiped under the bead by the stitching wheel 98, the latter being rotated by the toe of the bead. The smoothing roller 104 will press the turned portion firmly and smoothly 75 against the inner edge of the bead.

Having described my invention, what I claim as new and desire to secure by Letters Patent of the United States is:

1. A tire finishing machine having in combination, means for supporting and rotating an unfinished tire casing which has been removed from the building core, said means being constructed to engage a portion only 80 of the inside of the casing, and means for applying a side-wall and chafer strip to the 85 tire casing.

2. A tire finishing machine having in combination, means for supporting and rotating an unfinished tire casing which has been removed from the building core, said means 90 being constructed to engage a portion only of the inside of said casing, and means for guiding an assembled side-wall and chafer strip to said casing, and means for applying the said elements to the casing. 95

3. A tire finishing machine having in combination, means for supporting and rotating an unfinished tire casing which has been removed from the building core, said means being constructed to engage a portion only 100 of the inside of said casing, separating means over which an assembled side-wall and chafer strip are fed to prevent contact between the said strip and casing until a predetermined point in the path of travel of 105 the strip has been reached, and means for applying the side-wall and chafer strip to the casing.

4. A tire finishing machine having in combination, means for supporting and rotating 110 an unfinished tire, means for applying a side-wall and chafer strip to said tire, tire guiding means, and means to crowd the tire constantly in one direction to maintain it in operative relation with respect to said applying means. 115

5. A tire finishing machine having in combination, a support for engaging a portion only of the inside of a tire casing which has been removed from the building core, means 120 for applying a side-wall and chafer strip to said casing, and means for moving said means toward and from said support.

6. A tire finishing machine having in combination, means engageable with a portion only of the inside of a tire casing for rotating 125 an unfinished tire casing which has been removed from the building core, a roll for

applying a side-wall to said casing, and a roll for applying a chafer strip to the face of the bead.

7. A tire finishing machine having in combination, means engageable with a portion only of the inside of a tire casing for rotating an unfinished tire casing which has been removed from the building core, a side-wall applying roller, a chafer strip applying roller, and yielding means for urging the rolls toward each other.

8. A tire finishing machine having in combination, supporting means for engaging a portion only of the inner surface of a tire casing which has been removed from the building core, means for rotating said supporting means, means above said supporting means for applying a side-wall to the casing, and means adjacent said side-wall applying means for applying a chafer strip to the bead.

9. A machine for applying the side-wall and chafer strip to an unfinished tire casing, comprising means for rotating the casing, means to crowd the casing in a certain direction, means located above the rotating means for pressing the side-wall and chafer strip against the side of the casing and bead respectively, means for bodily moving the pressing means positively toward the rotating means to engage the casing, and spring means for moving the pressing means away from the rotating means to afford clearance for the removal of the work.

10. A machine for applying the side-wall and chafer strip to an unfinished tire, comprising means extending within the casing for supporting and rotating the latter, a side-wall pressure roller having a resilient work engaging surface and a guide flange to engage the heel of the bead, and a roller adjacent the side-wall roller and yieldingly pressed thereagainst adapted to press the chafer strip against the face of the bead, the said rollers being mounted on a pivoted arm and constructed for bodily movement toward and from the supporting means.

11. A machine for applying the side-wall and chafer strip to an unfinished tire casing, comprising means for guiding the said strips to said casing and separate them therefrom, means for pressing the strips against the side and bead of the tire, means for turning the chafer strip under the bead, and means for crowding the casing constantly in a certain direction to maintain it in operative relation with respect to the operating instrumentalities.

12. A machine for applying the side-wall and chafer strip to an unfinished tire casing comprising, a driven roller for rotating the casing, guide rolls tilted with respect to the radial line of the casing to constantly crowd the latter in one direction, means for rolling the side-wall and chafer strip

against the side and bead of the tire respectively, and means for stitching the chafer strip around and under the toe of the bead.

13. A machine for applying the side-wall and chafer strip to an unfinished tire casing comprising, a revolving support extending within the casing for rotating the latter, guide means tilted with respect to the medial line of the casing to constantly force it in one direction, a plurality of rollers above the said support for pressing the side-wall and chafer strip against the side of the casing and bead respectively, the said rollers being relatively yieldable, means for bodily moving the rollers toward and from the support, and means associated with said latter means for lifting the casing above the support to prevent rotation of the casing.

14. A machine for applying a side-wall and chafer strip to an unfinished tire casing comprising a support extending within the casing, means for continuously rotating the support, strip applying means located above said support, means for moving said applying means toward and from operative position, and means extending within the casing to elevate the latter above the support when the applying means are in inoperative position to prevent rotation of the casing by the support.

15. A tire finishing machine having in combination, means for rotating an unfinished tire casing, means for lifting the tire casing above the said means to prevent rotation of the casing, means for applying a side-wall to the side of the tire, means for applying a chafer strip to the face of the bead, means for gradually turning the chafer strip around the toe of the bead, means for stitching the chafer strip under the bead, and means for rolling the turned under portion against the inner side of the casing.

16. A tire finishing machine having in combination, means for supporting a tire casing, means extending within the casing for rotating the latter, means for preventing the rotation of the casing without stopping the rotating means, means for guiding an assembled side-wall and chafer strip to said casing, means arranged above said rotating means for applying the side-wall and chafer strip to the side of the tire and face of the bead, means for gradually turning the chafer strip around the toe of the bead, means for stitching the chafer strip under the bead, means for pressing the turned portion against the inner side of the casing, and means for crowding the tire casing toward the applying, turning and stitching means.

17. A tire finishing machine having in combination, means engageable with a portion only of the inside of a tire casing for supporting an unfinished tire casing which

has been removed from the building core, and means for applying a side-wall to the casing.

18. A machine for applying a side-wall to an unfinished tire casing, having in combination, a side-wall engaging roller having a guide flange adapted to engage the heel of the bead, a casing supporting roll below the said roller, means for moving the side-wall roller into engagement with a casing on said support, and means for rotating the support to drag the casing beneath the said pressure roller.

19. A tire finishing machine having in combination, means for applying a chafer strip to the bead of an unfinished tire casing which has been removed from the building core, and means engageable with a portion only of the inside of a tire casing for rotating a tire casing past said applying means.

20. A tire finishing machine having in combination, means for supporting and rotating an unfinished tire casing, said means being constructed and arranged to extend within the casing, means for applying a chafer strip to the bead of the casing, means for gradually turning the strip around the toe of the bead, and means operated by the toe of the bead for stitching the strip under the bead.

21. A tire finishing machine having in combination, means for supporting a tire casing, means for applying a chafer strip to the bead, means for gradually turning the strip around the toe of the bead, means for rotating the casing, and means rotated by the toe of the bead for stitching the strip under the bead, the speed of the stitching means being greater than the travel of the bead.

22. A tire finishing machine having in combination, means for supporting and rotating a tire casing, means for applying a chafer strip to the face of the bead, and means for stitching the strip onto the inner surface of the bead.

23. A tire finishing machine having in combination, means for supporting and rotating a tire casing, means for applying a chafer strip to the face of the bead, means for stitching the strip under the bead, and means for rolling the turned under portion against the inside of the casing.

24. A tire finishing machine having in combination, means for supporting and rotating a tire casing, means for applying a chafer strip to the face of the bead, means for gradually turning the strip around the toe of the bead, means for stitching the strip under the bead, and means for rolling the turned under portion against the inside of the casing.

25. A tire finishing machine having in combination, means for supporting and ro-

tating a tire casing, means for guiding a chafer strip to said casing, means for applying the strip to the face of the bead, means for gradually turning the strip around the toe of the bead, means for stitching the strip under the bead, and means for rolling the turned under portion against the inside of the casing.

26. A tire finishing machine having in combination, means for supporting a tire casing, means for applying a chafer strip to the face of the bead, and a toothed stitcher for kicking the strip under the bead.

27. A tire finishing machine having in combination, means supporting and rotating a tire casing, means for guiding a chafer strip to said casing, means shaped to conform to the face of the bead for pressing the chafer strip against the bead, and means for turning the strip onto the inner surface of the bead.

28. A tire finishing machine, having in combination, means for supporting an unfinished tire casing, means for applying a chafer strip to the face of the bead, and means for gradually turning the strip around the toe of the bead, said means including a series of tilted rollers having the axis of each successive roller arranged more closely to the vertical.

29. A tire finishing machine having in combination, means for supporting an unfinished tire casing, means for applying a chafer strip to the face and heel of the bead, means including a series of tilted rollers having the axis of each succeeding roller arranged more nearly to the vertical than the preceding one for gradually turning the strip around the toe of the bead, and a toothed stitcher for kicking the strip under the bead.

30. A machine for finishing tires having in combination, a support for an unfinished tire casing, a pressure roll shaped to conform to the face of the bead and adapted to apply a chafer strip thereto, means to gradually turn the strip around the toe of the bead, and means to stitch the strip onto the inner surface of the bead.

31. A tire finishing machine having in combination, means for supporting a tire casing in an inclined position, means extending within the casing for rotating the latter by engagement with the inner surface thereof, and means for disengaging the casing from the rotating means without interfering with the rotation of said means.

32. A tire finishing machine having in combination means for supporting an unfinished tire casing which has been removed from its tire building form, said means being adapted to engage a portion only of the inside of said casing, and means for applying a side wall and chafer strip to said casing.

33. A tire finishing machine having in combination means for supporting an unfinished tire casing which has been removed from its building form, said means being constructed to engage a portion only of its inner periphery, means for applying a side wall and chafer strip to said casing, and means for crowding the tire casing against said applying means.

34. A tire finishing machine having in combination means for supporting an unfinished tire casing which has been removed from the tire building form, said means being adapted to engage a portion only of the inside of said casing, and means for applying a finishing element to said casing.

EDWARD D. PUTT.
